UNITED STATES PATENT OFFICE.

CULLEN L. HUNTOON, OF LOS ANGELES, CALIFORNIA.

BAND PRESS FOR SHOE-SOLE PRESSES.

Application filed November 22, 1926. Serial No. 149,927.

My invention is a band press for shoe sole presses adapted for use in cementing soles to shoes.

An object of my invention is a simple form of press which may be used with a shoe last to clamp and hold soles while being secured to shoes by the cementing method, and retaining the sole in position while the cement sets.

Another object of my invention is the construction of a press connected to a shoe last which uses rubber bands which may be stretched to engage and hold the shoe sole in cementing operations, the rubber bands or elastics exerting a sufficient pressure on the sole to hold same in position while the cement sets.

In constructing my invention I utilize a shoe last on which supplemental lasts may be placed if desired, and have a series of rubber bands connected to the base or supporting structure of the last. These bands are so positioned that they may be readily stretched over the last, one band crossing over the other, if desired, and hence grip the sole of the shoe from the toe to the arch.

My invention is illustrated in the accompanying drawings, in which:

Figure 1 is a perspective view of my band press shown in operative relation to a shoe held on the last.

Figure 2 is a perspective view of the press showing the last and the bands in their loose position.

Figure 3 is a side elevation showing a shoe partly in section and the bands partly in section.

Figure 4 is a side elevation of the last with an extra shoe last placed on top of same showing the metal structure of the base with the grooves for rubber bands.

Figure 5 is a detail plan view, taken in the direction of the arrow 5 of Fig. 3, showing the manner of securing the bands to the metal base.

Figure 6 is a detail section on the line 6-6 of Fig. 3.

The metal structure of the press is formed substantially as follows:

A flat bearing plate 1 rests on a table or other support being secured thereto by the screw clamp 2, this being of an ordinary character and illustrating one way of fastening the last in position. A web 3 extends upwardly from the base and has a series of slots 4 in its upper edge 5 and also a se-

ries of enlarged transverse openings 6 directly below or connected with each slot.

A shank 7 extends upwardly from the base plate and from the web and preferably has lateral ribs 8 which are connected to the base or supporting ribs 9. A shoe last shape 10 is secured to the upper part of the shank and to the upper part of the ribs. This is of ordinary shape, such as used for ordinary lasts and, if desired, auxiliary lasts 11 of different sizes may be positioned on the fixed last 10.

A series of rubber bands 12 are secured in the web, these bands when loose being placed edgewise through the slots 4 and then turned flat so that they fit in the openings 6, these openings being substantially rectangular in shape and of sufficient length to accommodate the width of the bands and of sufficient depth to accommodate the thickness of the bands and of a series of packing strips 13. These strips are also formed of rubber and have a central perforation 14 to fit around the neck 15 formed in the web by the slots 80 and the transverse openings. These packing strips are stretched so that the head 16 formed at the upper part of the neck 15 may pass through the openings and thus allow the strips to close the slots 4. Thus when there are a series of rubber bands caught in the openings 6 with a series of over-lapping packing strips 13 secured on the neck portions 15 underneath the head part 16 of the web and closing the slots 4, these rubber bands cannot pull out of the slots.

The manner and use of my press is substantially as follows:

It will be understood that a shoe may be pressed on the last and as the sole is cemented, as in repair work, the rubber bands are stretched in such a manner as to over-lap and engage different portions of the shoe. For instance, the rubber band which is connected nearest to the shank 7 may be stretched to engage the toe portion of the sole, the band next thereto would be stretched to engage a part next towards the heel, and so on until the rubber band furthest from the shank would engage the sole near the arch or adjacent the heel of the shoe. One or more bands 17 may be secured in an opening 18 at the rear part of the shank, being inserted through a slot 19, and may be utilized to grip the shoe, preferably adjacent the toe, or to bind the other bands in position.

From the above description, together with

the drawings, it will be seen that the bands form in effect a double fan shaped structure when gripping the shoe and as each of the bands may be formed of rubber having considerable tensile power a heavy pressing stress may be exerted on the sole of the shoe. It will also be apparent that as the bands are operated one at a time that no great strength is required in clamping a shoe sole 10 on a shoe with my type of press. Moreover with this press when the rubber bands give out they are readily renewable and, as the metal is not subject to wear, the press may have a long life of service.

15 In illustrating my band press as applied to shoes, it is to be understood that it may be utilized for any other suitable device in which an article is desired to be clamped for a certain time in a certain position and this 20 clamping may be done by utilizing a series of rubber bands connecting over the article to the fixed structure to thus exert the desired pressure. From the above description it will be seen that I have invented a method 25 of holding articles in presses and a specific method of cementing shoes or other articles by successively gripping certain portions of the article by a resilient rubber band, applying sufficient bands extending over the 30 whole article to securely hold same in place and leaving the article the desired time.

Various changes may be made in the principles of my invention without departing from the spirit thereof, as set forth in the 35 description, drawings and claims.

I claim:

1. A band press comprising a shank, a work mounting device attached to the shank, a web connected to the shank having a series 40 of openings there-through, and elastic bands in said openings, said bands being stretchable over the work mounting device.

2. A band press having a shank with a work mounting device connected thereto, a web in a fixed relation to the shank, said web having a series of transverse openings and slots leading into said openings, and a series of elastic bands in the openings stretchable over the work mounting device.

3. A band press, as claimed in claim 2, the bands being positioned to engage different portions of work held on the work

mounting device, and said bands over-lapping one another.

4. A band press having a shank with a work mounting device connected thereto, a web having a fixed relation to the shank, said web having a series of transverse openings there-through, with slots forming entrance to said openings, the portion of the web between the openings forming a neck with a head between the slots, a series of bands in the openings, and a series of packing strips stretched over the heads and engaging the said necks, said packing strips forming closures for the slots and preventing removal of the bands.

5. A band press, as claimed in claim 4, the web being elongated with reference to the work mounting device, and the bands being positioned to engage different portions of work mounted thereon, said bands over-lapping one another.

6. A band press for a shoe sole press comprising a shank having a shoe last connected thereto, a web connected to the shank and positioned substantially parallel to the last, said web having a series of transverse openings, and elastic bands in said openings, the bands being positioned to engage different portions of the last in an over-lapping manner.

7. A band press, as claimed in claim 6, there being a slot in the base of the shank with an elastic band mounted therein, said band being adapted to stretch over the shank and to engage the toe portion of the last.

8. A band press for a shoe sole press comprising in combination, a bearing plate, means to clamp the plate to a table or the like, a shank connected to the plate having a last form on its outer end, a web extending from the shank and connected to the bearing plate, said web having a series of transverse openings with slots forming an entrance to said openings, and a series of elastic bands fitted in the openings, said bands being positioned to engage different portions of the last form in an over-lapping manner.

In testimony whereof I have signed my name to this specification.

CULLEN L. HUNTOON.
